UNITED STATES PATENT OFFICE.

FOREST L. GRAY, OF KENMORE, OHIO.

HAIR CUTTER.

1,404,603.

Specification of Letters Patent. Patented Jan. 24, 1922.

Application filed August 13, 1920. Serial No. 403,200.

To all whom it may concern:

Be it known that I, FOREST L. GRAY, a citizen of the United States, residing at Kenmore, in the county of Summit and 5 State of Ohio, have invented new and useful Improvements in Hair Cutters, of which the following is a specification.

This invention relates to certain new and useful improvements in hair cutters and particularly to new and improved parts therefor.

A particular object of the invention is to provide an attachment for hair cutters whereby hair may be evenly fed to the cutting shears and, which in use with a hair cutter, will provide means whereby hair may be evenly and uniformly cut in a relatively short period of time.

Further objects are to provide a strong, 20 durable hair cutting device, of simple, economical construction, and particularly a power operated device of the type commonly known as hair clippers, which may be used to advantage in cutting long, as well as short 25 hair.

The above and other apparent objects are accomplished and other ends are attained by the novel construction, combination and arrangement of parts herein disclosed and 30 illustrated in the accompanying drawings, wherein I have shown a preferred embodiment of my invention, it being understood that changes, variations and modifications may be made or substitutions resorted to 35 which come within the scope of the matter hereinafter claimed.

In the drawings which form a part hereof and in which I have employed similar numerals of reference to indicate corresponding parts throughout the several 40 views,

Figure 1 is a perspective view of the lid or top part of the handle of my improved hair cutting device.

45 Figure 2 is a perspective view of the same having the lid shown in Figure 1 removed to more clearly illustrate the several parts and the improved arrangement of same.

Figure 3 is a central, vertical sectional 50 view taken as indicated by the lines 3—3 of Figure 2.

Figure 4 is a sectional view of the feeding

brush and brush supporting arm taken as indicated by the lines 4—4 of Figure 3.

Figure 5 is a fragmentary sectional view 55 of the arm employed to support the rotary feeding brush.

Proceeding now to a detailed description of the invention, with particular reference to the embodiment thereof illustrated in the drawing, the numeral 6 is used generally to denote a cutter frame which is shaped at one end to form a hollow handle 7 and has a central portion which forms the casing 8. The lower end of said frame 6 forming a 60 cutting head 9. The cutting head comprises a serrated base plate 10 which may be integral with the frame 6 or attached thereto and a reciprocating serrated knife 11 which is positioned on said plate 10, with the serrated edges of the plate and the knife forming a cutting or clipping shears. The base plate is provided with guide pins 12 and the knife with the slots 13 which are adapted to receive said pins 12 so that the knife is 65 limited to a lateral movement. With the base plate in a horizontal position, the frame extends upwardly from the rear thereof at approximately a right angle thereto and is enlarged to form the housing 8. A shaft 14 70 is journaled in the sides of the casing 8 so as to extend laterally thereacross and the said shaft 14 is provided with a cylindrical member 15 which is coaxially and rigidly fixed thereto. The cylindrical member or drum 75 15 is provided with a circumferentially extending, serpentine groove 16. An actuating lever 17 is pivotally secured to the frame 80 6 by the screw bolt 18 or other suitable means, with the upwardly projecting end of 85 the lever 17 seated in the groove 16 of the drum 15 and the said lever extends downwardly from said pin 18, then inwardly in parallel spaced relation to the base plate 10 and terminates in a downward turned end 90 which is positioned in a suitable slot 20 in the rear edge of the knife 11 so that a rotation of the drum 15 will cause a reciprocating movement of the lever 17 and impart a reciprocating movement to said knife 11. 95

The lever is enlarged as at 21 and is provided with a laterally directed slot 22 so that the retaining screw 24 may be positioned therein without interfering with the reciprocating

ing movement of the lever 17. A lid 23 which is provided for the cutting head 9 is held in position by the retaining screw 24 which extends through the slot 22 and is 5 threaded in a suitable bore 25 in the bed of the cutter head 9. A toothed wheel 26 is coaxially and rigidly fixed on a shaft 14 adjacent one end thereof. The handle 7 is inclined upwardly from the casing 8 and a 10 drive shaft 27 extends longitudinally therethrough. The drive shaft is mounted in suitable bearings 28 and extends through the casing 8 and into the housing or brush supporting arm 29. A worm 30 is coaxially and 15 rigidly fixed on the shaft 27 so that the threads of the worm will engage the teeth on the wheel 26.

The housing 29 is threaded into or otherwise secured to the casing 8 as at 31 and is 20 provided on its downwardly extending end with a cap 32 which is threaded therein and provided with suitable bearings in which the free end of the drive shaft 27 is mounted. The free end of the housing 29 is enlarged 25 and the shaft 33 is journaled in said enlarged portion of said housing and in a bearing in the cap 34 which is threaded in the outer lateral side of the enlarged portion of said housing so that the axis of the shaft 30 33 will be at a right angle to the axis of the shaft 27. A toothed wheel 35 is coaxially fixed to the shaft 33 and a worm screw 36 is fixed to the shaft 27 so that the threads of 35 the worm 36 will engage the teeth in the wheel 35. By this arrangement, a rotary movement of the shaft 37 will impart a relatively slow rotary movement to the shaft 33. The shaft 33 extends laterally from the free 40 end of the housing 29 in parallel spaced relation to the serrated edges of the plate 10 and the knife 11. A segmental portion of the shaft 33 is removed from the shaft 33 to provide a flat surface 37 and a cylindrical brush is adapted to be detachably secured 45 on the shaft 33 with its circumferential edge in approximate contact with the serrated edge of the knife 11. The brush 38 comprises a hollow core provided with a bore adapted to receive the shaft 33, so as to be 50 rotatable therewith. The core 39 is provided with a plurality of closely set brush tufts 42 which project radially therefrom. The inner end of the core 39 is provided with a spring 41 which is adapted to snap into the 55 circumferentially extending groove 40 on said shaft 43 when the brush is positioned thereon and is thus retained in position so that it will not be unintentionally removed therefrom.

60 In use, the slotted end 43 of the shaft 27 is connected in the usual manner to a source of power, this is usually done by employing a flexible shaft which is driven by an electric motor or other suitable means.

65 It is obvious that the rotation of the shaft

27 will cause a rotary movement of the worm screw 26 and thus impart a rotary movement to the drum 15 and cause a reciprocating movement of the lever 17 and impart a similar movement of the knife 11, thus providing a practical, highly efficient means for 70 operating said knife.

It is also obvious that the rotary movement of the drive shaft 27 will cause the brush 38 to revolve in the direction of the 75 arrow shown in Figure 3. The free ends of the hair may be thus fed to the shears formed by the serrated edges of the plate 10 and the reciprocating knife 11.

While the member 38 has been shown and 80 described as a brush, it is to be understood that the invention contemplates the employment of a reel or any other suitable device which may be rotatably secured in a similar position so as to feed the hair to said shears. 85 And while I have shown and described an improved clipper having a rotary feeding member 38 positioned thereon as a part thereof, it is also to be understood that the rotary member 38 may be made a part of 90 any hair cutting device and may be manufactured and used in the form of an attachment which may be secured to any form of clippers or cutters.

Having thus described my invention what 95 I claim as new and desire to secure by Letters Patent is:—

1. The combination with a hair cutter, having a serrated base plate and a reciprocating serrated knife, of a cylindrical brush 100 rotatably fixed to said cutter with its axis in parallel relation to said knife and spaced therefrom so that the peripheral surface of the brush will be in approximate contact with said knife, and means to reciprocate 105 said knife and rotate said brush.

2. A hair cutter comprising the combination of a hair clipper and a member rotatably secured thereto so as to engage the material to be cut and bring it into contact 110 with the shears on said clipper, means to operate said clipper and means to rotate said member.

3. In a hair cutter, a cutting head comprising a serrated plate, a serrated knife 115 positioned thereon so as to be laterally movable in relation thereto, a supporting frame extending upwardly at approximately a right angle to said plate, a drum rotatably mounted in said frame, a circumferentially extending, peripheral groove around said drum, a lever fulcrumed on said frame, with one end thereof positioned in said groove, and with the other end thereof engaging said knife, and means to rotate said drum. 120

4. In a hair cutter, a cutting head comprising a serrated plate, a serrated knife positioned thereon so as to be laterally movable in relation thereto, a supporting frame extending upwardly at approximately 130

a right angle to said plate, a drum rotatably mounted on said frame, a circumferentially extending groove around said drum, a lever fulcrumed on said frame, with one end thereof in said groove and with the other end thereof engaging said knife, a rotatable member secured to said frame so as to overlie the serrated edges of said knife and en-

gage the material to be cut and bring it into contact with said knife and means to simultaneously rotate said drum and said member substantially as and for the purpose herein set forth. 10

In testimony whereof I have hereunto set my hand.

FOREST L. GRAY.
